(57) CLAIM

We claim, the ornamental design for an LED wall fixture, as shown and described.

DESCRIPTION

FIG. 1 is an upper perspective view of the LED wall fixture. FIG. 2 is a lower perspective view thereof.

FIG. 3 is a top plan view thereof.

FIG. 4 is a front elevational view thereof.

FIG. 5 is a side elevational view thereof, the side elevational view from the opposite side of the LED wall fixture being the same; and,

FIG. 6 is a bottom view of the LED wall fixture.

Any broken lines shown in FIG. 1-FIG. 6 depict portions of the LED wall fixture that form no part of the claimed design.
